UNITED STATES PATENT OFFICE

109,650

DESIGN FOR A SERVICE STATION CANOPY

Ralph N. Aldrich and Alfred H. Jaehne, San Francisco, Calif., assignors to Standard Oil Company of California, San Francisco, Calif., a corporation of Delaware

Application March 2, 1938, Serial No. 75,500

Term of patent 7 years

To all whom it may concern:

Be it known that we, Ralph N. Aldrich and Alfred H. Jaehne, both citizens of the United States of America, residing in the city and county of San Francisco, State of California, have invented a new, original, and ornamental Design for a Service Station Canopy, of which the following is a specification, reference being had to the accompanying drawing, forming part thereof,

We claim:
The ornamental design for a service station canopy, as shown.

RALPH N. ALDRICH.
ALFRED H. JAEHNE.
